CLAIM

The ornamental design for a dispensing container lid, as shown and described.

DESCRIPTION

FIG. 1 is an isometric view of the dispensing container lid in a closed configuration with a pivoting handle of the dispensing container lid in an upright, primary position.

FIG. 2 is a front elevation view.

FIG. 3 is a rear elevation view.

FIG. 4 is a left side elevation view.

FIG. 5 is a right side elevation view.

FIG. 6 is a top view.

FIG. 7 is a bottom view.

FIG. 8 is a left side view of the dispensing container lid with the pivoting handle oriented in a secondary position; and, FIG. 9 is an isometric view thereof.

The broken lines in the drawings depict portions of a dispensing container lid that form no part of the claimed design.
